RADIO RECEIVING SYSTEM

Thomas A. Marshall, San Pedro, Calif.

Application July 1, 1936, Serial No. 88,389

4 Claims. (Cl. 250—8)

(Granted under the act of March 3, 1883, as
amended April 30, 1928; 370 O. G. 757)

My invention relates broadly to superheterodyne radio receivers and more particularly to a superheterodyne receiver having a cyclically varied conversion oscillator and highly selective circuits for the elimination of distortion, noise and atmospheric disturbances in the reception of signals.

One of the objects of my invention is to provide a radio receiving system which will clearly and efficiently receive signals of very high carrier frequencies which are especially subject to distortion and critical under control so that reliable reception thereof is difficult.

Another object of my invention is to provide a radio receiving circuit for the reception of high frequency signal energy in which the use of highly selective circuits is made possible by the adjustment of the carrier frequency over considerable ranges of variation to pass the selective circuits to the exclusion of distorting and interfering energy.

A further object of my invention is to make possible the employment of tone discrimination in the reception of continuous wave signals at ultra-high frequencies.

Still another object of my invention is to provide a superheterodyne radio receiving system for the reception of ultra-high frequency signals, wherein tone discrimination is made possible by modulating the intermediate frequency current at a stable audio frequency and keying the audio modulation by the signal received.

A still further object of my invention is to provide a superheterodyne radio receiving system for the reception of ultra-high frequency signals, wherein the signals are impressed on the first detector and are effective in the intermediate frequency amplifier under the control of an oscillating current operative to influence the output of the conversion oscillator; the intermediate frequency amplifier being particularly selective to pass only the desired frequency band.

Another object of my invention is to provide a superheterodyne radio receiving system for the reception of ultra-high frequency signals wherein the signals are intermittently passed to the intermediate frequency amplifier, and all distortion, atmospherics, and man-made static are effectively excluded from the output during the periods between the intermittently passed signals.

Other and further objects of my invention reside in the circuit arrangement and modifications thereof hereinafter more fully described, with reference to the accompanying drawing, which is a schematic diagram of the circuit employed in the receiving system of my invention.

In the reception of signals at ultra-high frequencies, it is desirable to provide a highly selective circuit in the receiving system in order to exclude distortion arising from frequency

modulation and harmonics of the modulating signals, and also interfering energy such as arises from atmospheric disturbances, man-made static, or internal circuit imperfections. In C. W. reception, the practice known as "tone discrimination" is extremely useful and has been made practical in the reception of comparatively low frequencies. But so far, tone discrimination has not been satisfactorily accomplished in the field of ultra-high frequency reception due to variations in the local oscillator frequency and in the transmitter frequency. Any variation in the oscillator frequency for obtaining heterodyne reception of the incoming frequency will change the beat frequency, which is usually made 1,000 cycles and amplified in a peaked audio amplifier. Should the beat frequency be changed even slightly, tone discrimination will no longer be useful, and if the frequency of the transmitter varies, the signal will likely not be heard. For low frequency reception, better stability of frequency and less percent variations in the operation of the transmitters and local oscillator are obtained and tone discrimination is practical.

In the reception of voice modulated high frequency waves, the practice of tone discrimination is not applicable but an analogous operation, employing the same circuit arrangement, is possible with merely an adjustment of the frequencies of operation as will hereinafter be more fully set forth.

Tone discrimination in C. W. reception at high and ultra-high frequencies is obtained in the system of my invention by using a tuned audio system, and a super-heterodyne receiver, and by modulating the intermediate frequency current by varying the oscillator output with a modified type of relaxation oscillator which is adjusted to 1,000 cycles. The intermediate frequency current is therefore modulated at 1,000 cycles, and is detected by an ordinary rectifier instead of by the beat frequency oscillator method. Thus, all signals are received as if they were actually transmitted with a modulation of 1,000 cycles, and tone discrimination is possible.

Referring to the drawing in more detail, I provide an antenna 1 and a pre-selector tuning circuit 2 connected with the input of a radio frequency amplifier stage 3 through a coupling condenser 4. A balanced, non-oscillating first detector circuit employing electron tubes 5 and 5' has the inductance 6 in the input circuit thereof coupled with the inductance 7 which is connected in the output circuit of the radio frequency amplifier 3. An inductance 8 is connected between the anodes of the tubes 5 and 5' and has a center tap connection 8' thereto for connection to the anodes of the balanced detector. The inductance 8 is coupled with the input circuit of the first detector through the inductance 6, but oscilla-

tion of the detector is prevented under the control of a variable resistance **9** connected with screen grids in the tubes **5** and **5'**.

I provide also a balanced circuit for the conversion oscillator which includes electron tubes **10** and **10'**, inductance **11** connected with the control grids thereof and inductance **12**, coupled with inductance **11**, connected with the anodes thereof. A variable condenser **14** is connected in shunt with inductance **11**, and is operable to control the frequency of oscillation of the conversion oscillator in the usual manner through a gang control arrangement with tuning condensers **15** and **16** in the radio frequency amplifier **3** and the first detector circuit, respectively, as indicated by the dotted line **17**.

The output of the conversion oscillator is coupled with the first detector, wherein it beats with energy at the received frequency to produce currents at the desired intermediate frequency, through the inductance **8** via the high frequency coupling condenser **18**, which is of approximately 100 mmf. capacity, the conductor **19**, and the center tap **8'**. The output of the first detector, at the intermediate frequency is fed through the tap **8'** and conductor **20** to the intermediate frequency amplifier as will be hereinafter more fully considered.

In addition to and in cooperation with the usual functions in a superheterodyne receiver, I provide a relatively low frequency oscillator **21**, which is a modified relaxation type of electron tube oscillator and will generate an output of constant frequency. Means comprising a variable resistor **22**, connected in the cathode circuit of the oscillator **21**, is provided for adjusting the frequency of operation of the oscillator **21**. In C. W. reception, as now being considered, this frequency may be an audio frequency of 1000 cycles per second. Measurements on this oscillator, operating at 1000 cycles, showed that its frequency varied but 3 cycles over a period of five hours. A variable anode voltage of 90 volts plus or minus 10 percent gave a frequency variation of approximately 10 cycles. No variation in frequency was observed by varying the heater voltage from 2 to 2.5 volts.

The low frequency auxiliary oscillator **21** is connected with the conversion oscillator through a high frequency choke coil **23**, a low frequency coupling condenser **24**, which is of approximately 1 mfd. capacity, conductor **25**, and center tap **12'** on the inductance **12**, whereby the output of the low frequency oscillator **21** modulates the output of the conversion oscillator. In the case of C. W. reception, the output of the conversion oscillator is modulated by a constant 1000 cycle per second audio frequency. In the first detector, this modulated current entering at **8'** divides between the two halves of the inductance **8** on either side of the center tap and equally affects the control grids of the tubes **5** and **5'** by reason of the coupling between inductances **8** and **6**. When no signal is received on antenna **1** and in inductance **7**, the modulation of 1000 cycles will not be heard by the listener because of the absence of an intermediate frequency current. When a signal is received and passes through inductance **7**, the control grids of the tubes **5**, **5'**, are oppositely affected thereby because of the unbalanced coupling of the inductance **7**, and a beat frequency will be generated from the combination of the signal and the local oscillator output. The first detector thus produces an output at the beat frequency which is the intermediate frequency

current of the superheterodyne receiving system, and this intermediate frequency current is modulated at 1000 cycles from the output of the auxiliary oscillator **21**.

The modulated intermediate frequency current is fed through conductor **20** to the intermediate frequency amplifier stages **26** and **27** and to the second detector **28** in the output of which appears the 1000 cycle modulation in the character of the signal received. In the output of the second detector, I have provided a low pass filter **29** and a band pass filter **30** in order to effectively exclude all energy except the 1000 cycle signal. This is possible because of the stability of the 1000 cycle wave which is generated in the auxiliary oscillator **21**. Peaked audio frequency amplifier stages **31** and **32** complete the receiving circuit to the telephone receivers **34**. The listener hearing the constant 1000 cycle note in the character of the signal may therefore easily discriminate in tone between the signal and any interference that may be present in the telephones.

I have shown in the drawing merely the terminals of the power supply circuits and the connections at **x**, **x'**, which interconnect the heater elements in the various tubes shown. Volume control means are shown at **35** and **36**; and choke coils **37** and bias resistors **38** are shown distributed in the power connections as required. By-pass condensers **39** likewise are provided where necessary.

In the system of my invention as shown and described, static appears to be received as a highly damped oscillation and does not unbalance the detector by acting in the inductance **7** as a "signal". It is, therefore, not heard in the telephones at 1000 cycles when a tuned audio system is employed as shown. It appears also that crashes and noise do not effectively unbalance the first detector, so that clear reception is had on all high frequency bands. Thus, the system of my invention is extremely useful in the elimination of noise, static and internal amplifier noise, and reception at the high frequencies is, therefore, greatly improved.

A further useful advantage of the system of my invention will be seen in ultra-high frequency multiple reception work, that is, intermittent reception from a number of communication stations all transmitting at or near the same frequency. Heretofore such operation has not been successful on ultra-high frequencies due to the fact that crystals used for controlling the frequencies of the several transmitters are not all ground to the same frequency but to frequencies differing by several kilocycles. Higher accuracy in the grinding of the crystals to insure substantially identical frequencies of operation is impracticable. By employing a modulated intermediate frequency current in the superheterodyne receiver, the circuits can be made to cover as wide a range as 16 kilocycles by adjusting the intermediate frequency band pass tuning system, or by obtaining from the second detector through the beating of incoming signals of various frequencies with the output of the conversion oscillator and the output of the auxiliary oscillator, beat frequencies which will be passed by peaked intermediate frequency amplifier circuits.

The latter instance will obtain, for example, when an oscillator frequency of 20,465 kilocycles is modulated by a 1000 cycle oscillation to produce beats of 20,466 and 20,464 kilocycles. Con-

sidering that these beat frequencies will also beat to produce a 2 kilocycle note and that the second harmonic of the modulation is 2 kilocycles, further beat frequencies of 20,461 to 20,464 and 5 20,466 to 20,469 kilocycles, as well as the fundamental frequency of 20,465 kilocycles, will be present in the first detector to beat with the signal energy. Signal energy therefore of any frequency between the limits of 19,996 and 20,004 10 kilocycles will produce a beat frequency in the output of the first detector of 465 kilocycles which will be passed by a peaked 465 kilocycle intermediate frequency amplifier.

Considering, now, voice modulated currents received at the antenna 1 from a single transmitter operating at ultra-high frequency, and the frequency of which is susceptible of rather broad variation, such as within the range above noted in which a number of C. W. transmitters were 20 considered operating. Such a voice modulated current, varying in frequency, can be received by the system of my invention in a manner similar to that just previously described. One important adjustment is required to be made, namely, in 25 the frequency of the auxiliary oscillator which must obviously be of super audible frequency in order that the output thereof will not be heard in the telephones. This adjustment can be made by merely varying the resistance 22 in the cathode circuit of the auxiliary oscillator 21. Coupling condenser 24 may also be varied to transmit the higher frequency more efficiently; and the filters 29 and 30 also may be adjusted for the modified operation of the system. Also, as 35 only one station is to be received, the intermediate frequency amplifiers 26, 27, may be limited to respond only to a narrow frequency band which embraces the voice modulations. The advantages of noise suppression, and distortion removal and 40 prevention, noted with respect to the operation of the system of my invention in C. W. reception, obtain also in the reception of voice modulated currents.

While the system of my invention is primarily 45 intended for use in C. W. reception on ultra-high frequencies, as hereinbefore set forth, I desire it understood that modifications may be made within the scope of my invention along the lines indicated with respect to the reception of voice modulated currents, and along other lines, and that 50 no limitations upon my invention are intended except as are imposed by the appended claims.

The invention described herein may be manufactured and used by or for the Government of 55 the United States of America for governmental purposes without the payment of any royalties thereon.

What I claim as new, and desire to secure by Letters Patent of the United States, is as follows:

1. In a superheterodyne high-frequency continuous wave signal receiving system, in combination, a first detector comprising a balanced electron tube circuit having a balanced input circuit and a balanced output circuit in coupled relation, a local oscillator, means for modulating said local oscillator at a constant audible frequency, means for impressing the output of said modulated oscillator on said first detector through 65 said output circuit in balanced relation, means for impressing incoming continuous wave signals

on said first detector in unbalanced relation whereby said electron tube circuit is unbalanced and current flows in the said output circuit at the beat frequency of said incoming signal and the local oscillation, in the character of the incoming signal, and modulated at said constant audible frequency, an intermediate frequency amplifier operative at said beat frequency, a second detector, and a peaked audio frequency amplifier for selectively amplifying said modulation. 10

2. In a superheterodyne high-frequency voice modulated signal receiving system, in combination, a first detector comprising a balanced electron tube circuit having a balanced input circuit and a balanced output circuit in coupled relation, 15 a local oscillator, means for modulating said local oscillator at a constant inaudible frequency, means for impressing the output of said modulated oscillator on said first detector through said output circuit in balanced relation, means for 20 impressing incoming voice modulated signals on said first detector in unbalanced relation whereby said electron tube circuit is unbalanced and currents of beat frequencies are produced in said first detector, an intermediate frequency amplifier, 25 certain of said beat frequencies produced in said first detector corresponding to the frequency of operation of said intermediate frequency amplifier, a second detector, and an audio frequency amplifier for amplifying the voice modulations 30 detected in said second detector.

3. In a superheterodyne high-frequency signal receiving system, a first detector comprising a balanced electron tube circuit having a balanced input circuit and a balanced output circuit, 35 center-tapped inductances in said input and said output circuits arranged in coupled relation, and a third inductance coupled with said center-tapped inductances, means including the center-tapped inductance in said output circuit for impressing modulated local oscillations on said input circuit in balanced relation, means including 40 said third inductance for impressing signal energy on said input circuit in unbalanced relation, and an intermediate frequency amplifier operatively 45 connected with said first detector through the center tap of said inductance in the output circuit thereof for receiving modulated oscillations of beat frequency in the character of the signal energy. 50

4. In a superheterodyne high-frequency signal receiving system, a first detector comprising a pair of electron tube devices having input circuits connected in push-pull relation and output circuits connected in parallel relation, center-tapped inductances in said input and said output circuits arranged in coupled relation, and a third inductance coupled with said center-tapped inductances, means including the center-tapped inductance in said output circuits for impressing 60 modulated local oscillations on said input circuit in balanced relation, means including said third inductance for impressing signal energy on said input circuit in unbalanced relation, and an intermediate frequency amplifier operatively connected with said parallel connected output circuits for receiving from each of said electron tube devices modulated oscillations of beat frequency in the character of the signal energy. 65
